UNITED STATES PATENT OFFICE.

WILLIAM SMITH, OF PORTLAND, OREGON.

COMBINATION DRAFTING INSTRUMENT.

972,936.

Specification of Letters Patent. Patented Oct. 18, 1910.

Application filed September 22, 1909. Serial No. 519,078.

To all whom it may concern:

Be it known that I, WILLIAM SMITH, a citizen of the United States, residing at the city of Portland, in the county of Multnomah and State of Oregon, have invented certain new and useful Improvements in Combination Drafting Instruments, of which the following is a specification.

This invention relates to that class of mathematical instruments in which two or more members are conjoined for the purposes of drawing predetermined, or experimental lines, or diagrams, according to measurement,—and the object of my invention is to produce, in simple, cheap and efficient form, a combination drawing and measuring instrument, or tool, which shall embody all the instrumentalities ordinarily required for use in delineating geometrical work, and while designed to be sufficiently accurate in construction and operation for any regular draftsman's service, it will be found especially valuable for beginners, students and school attendants generally, as a practical means of education in measurements, lines, angles and circles, as well as handy as a plain ruler, measure and scale for any purpose.

Briefly speaking, my invention embodies in one instrument three main members, viz: a ruler, graduated or scaled to inches and fractions thereof,—a protractor, divided into degrees and fractions of the circle,—and a slide adapted to be removably-fitted with a pencil or stylus for serving as a compass in drawing circles and lines radiating from the center of the protractor,—these three members being permanently or adjustably connected together,—all as will more fully appear by the following detailed description and by reference to the accompanying drawing forming part of this specification.

In the drawing, similar letters of reference indicate like parts in the several figures.

Figure 1 is a plan or face view of one of the simpler forms of my instrument. Fig. 2 is a cross section on line 2, 2, Fig. 1. Fig. 3 is a similar section on line 3, 3, Fig. 1. Fig. 4 is a plan of a modification of my invention, Fig. 5 is a plan of part of the ruler, showing a modified construction thereof, and of the slide. Fig. 6 is a cross section on line 6, 6, Fig. 5.

A is a flat rule, graduated, by preference, into inches and fractions thereof, along one edge, to serve as a measure,—and to inches, and say, tenths, along the other edge to pro-

vide a handy scale for use of the draftsman in contingencies where same may be required.

a is a slot extending centrally of and parallel with the edges just named, and preferably open at the outward extremity. This slot is discontinued so as to leave a solid portion of the rule toward its inner end where it is pivoted to the center of a protractor B, beyond which pivot point the rule *a* terminates in a finger or indicating pointer *a*² the point of which is in alinement with the center of the slot *a*, in Fig. 1, and with the left-hand edge of the rule A in the modification shown in Fig. 4.

As seen in all the figures, the rule A with its pointer or finger *a*², is superposed upon the protractor B, and I have shown a simple form of pivot in the shape of a hollow rivet *b*, it being intended that a needle point (such as commonly used in drawing tools) shall be passed down through the central aperture *B*¹ and into the paper or board being drawn upon. This rivet *b* is preferably countersunk into the lower face of the hub of the protractor so that it may lie level.

*b*¹, *b*¹, represent a plurality of extra holes through which extra needles may be passed to assist in steadyng the work at any point as will be readily appreciated.

The protractor B is divided and graduated into degrees of the circle, and preferably also into minutes and seconds.

C is a slide, or cross head, superposed upon the rule A, perforated at its center, and preferably provided with a hollow rivet, or thimble *C*¹, the under flange of which will slide along the under side of the rule A, overlapping the slot *a* therein, so as to retain the slide C in operative position. The hollow center or aperture *C*² of this rivet or thimble is of such a diameter as will adapt it to receive a marking device such as a pencil, pointed lead, stylus or ruling pen, according to requirements,—and I provide a set screw *C*² passing transversely through a proper way in the slide and thimble for securing such marking device when same has been set and is to be operated. Another pointed set screw *d* passes vertically through the slide C at one side thereof and impinges upon the surface of the rule, to hold the slide and its marking device at any fixed point. *c*¹, *c*¹, are fingers projecting from the sides of the slide C so as to register with any predetermined point on the rule or scale.

In the modification shown in Fig. 4, the rule A is offset from the protractor B, the left-hand edge of said rule being alined with the center of the protractor and consequently with the needle point when inserted in the aperture B¹; the same style of indicating finger a² as in Fig. 1, being used, but projecting from a specially formed hub B², so as also to be in line with the edge of the rule just named. This arrangement will suit some purposes better than the former style described as for Fig. 1, as lines can thus be drawn outward by a separate pencil or pen, from the periphery of the protractor B along the clearly-exposed edge of the rule A, (instead of having to be made inside the slot a₁) in all cases where accuracy is desired in the use of the combined rule, compass and protractor. The rule A, of course, is intended to be used, if desired, simply as a ruler and measure. In Fig. 4 I have shown a detachable cap D at the outer end of the rule A. This cap may be used, if desired, to store extra needles, leads, etc., as well as to prevent the slide C from passing out of the slot a and thus being, perhaps, mislaid when the instrument is out of use.

In the modification, Figs. 5 and 6, I have made the body of the rule A, and also the slide C, with raised central portions, A¹ and C¹, respectively, which enables the lower end of the rivet C to be conveniently countersunk, and tends to stiffen the rule as well. All other parts of the device will remain the same.

The operations of the different parts of my improved instrument, as well as those of the component members when used in combination will be so well understood from the foregoing, and from the drawing, as not to here require further explanation. I may say, however, that I do not limit myself to any of the precise details of construction as to pivot points, contours of parts, graduations of rules and scales, or any other specifically described feature, as these may all be varied or modified according to judgment, or special requirements, without departing from the principle or sacrificing the advantages of my invention. And furthermore, I may employ steel, brass, nickel, aluminum, or any other metal or metals, or alloys,—or gutta percha, celluloid, wood,

or other material or compound, without prejudice to the article in manufacturing the same.

What I claim and desire to secure by Letters Patent is as follows:

1. A combination drafting instrument, composed, essentially, of the following instrumentalities, viz:—a graduated rule having straight edges for the greater portion of its length, a longitudinal slot parallel to and between such edges, and an indicating finger projecting from its inner end,—a protractor upon which said rule is superposed in such manner that said finger may register with any point on the rim of said protractor,—a hollow rivet serving as a central pivot for said protractor, as a means of connection thereof with said rule, and also adapted to receive a needle point,—and a slide movable in the slot in the rule and having a pointer at its side adapted to register with any point on the rule, and a central aperture for the reception of a marking device,—all substantially as and for the purposes set forth.

2. A combination drafting instrument, composed, essentially, of the following instrumentalities, viz: a graduated rule having straight edges for the greater portion of its length, a longitudinal slot parallel to and between such edges, and an indicating finger projecting from its inner end,—a protractor upon which said rule is superposed in such manner that one edge of said rule is in direct alinement with the center of said protractor, and also so that said finger may register with any point on the rim of said protractor,—a hollow rivet serving as a central pivot for said protractor, as a means of connection thereof with said rule, and also adapted to receive a needle point,—and a slide movable in the slot in the rule and having a pointer at its side adapted to register with any point on the rule, and a central aperture for the reception of a marking device,—all substantially as and for the purposes set forth.

Signed at the city of Salem, State of Oregon, this 30th day of July, 1909.

WILLIAM SMITH.
